LLP

(57) **CLAIM**

The ornamental design for a cleaning device with tail swab, as shown and described.

DESCRIPTION

FIG. 1 is a perspective view of the cleaning device with tail swab of the present invention;

FIG. 2 is a side elevational view thereof;

FIG. 3 is an opposite side elevational view thereof;

FIG. 4 is a top view thereof;

FIG. 5 is a bottom view thereof;

FIG. 6 is a front elevational view thereof enlarged for clarity; and,

FIG. 7 is a rear elevational view thereof enlarged for clarity. The broken away symbols in the drawings indicate that any portion of the article beyond what is shown forms no part of the claimed design.

1 Claim, 4 Drawing Sheets
